(57) **CLAIM**

The ornamental design for a connector for a fluid container, as shown and described.

DESCRIPTION

FIG. 1 is a front perspective view of a connector for a fluid container showing the new design.

FIG. 2 is a first side view thereof.

FIG. 3 is a second side view thereof.

FIG. 4 is a top view thereof; and,

FIG. 5 is a bottom view thereof.

The broken lines shown in the figures illustrate portions of the connector for fluid container that form no part of the claimed design.
